UNITED STATES PATENT OFFICE.

GUY R. COYNE, OF MILWAUKEE, WISCONSIN, ASSIGNOR TO UNITED SHOE MANUFACTURING CORPORATION, OF PATERSON, NEW JERSEY, A CORPORATION OF NEW JERSEY.

STAPLE-INSERTING MACHINE.

Application filed October 4, 1926. Serial No. 139,438.

This invention relates to staple-inserting machines and is illustrated herein as embodied in a machine arranged to form staples from wire and to drive the staples into shoe parts.

Among the uses to which staple-inserting machines of this character are put in the manufacture of McKay shoes is the sole-laying operation. In performing this operation an outsole is positioned by the operative in the proper relation to a lasted shoe upper and insole. The operator then presents the work to the nozzle of the staple inserting machine, usually inserting a staple at each end 15 of the tip line, a pair of staples at the ball of the sole, a pair of staples in the shank, and two or three staples in the heel-seat. In case of women's shoes having pointed toes, a number of closely spaced staples are often inserted around the toe to take the place of the McKay stitching which then extends only about to the tip line. When inserting the staples the shoe is presented with its toe toward the machine and is moved lengthwise 25 between the insertion of successive staples so that the staples at the tip line, the ball and the shank portion of the sole are inserted in that order, being driven into the groove of the McKay outsole or into the shoulder of the 30 channel closely adjacent to the groove. All of these staples are clenched upon the iron bottom with which a McKay last is commonly provided.

As staple inserting machines of this character are commonly organized, the staples are formed and driven with their bars parallel to the front of the machine. Thus when they are driven into the channel or groove of the sole of a shoe which is to be McKay stitched, 40 the bars of such of the staples as lie in the shank or ball portion of the sole, indeed the bars of all the staples except those driven into the heel-seat and at the extreme toe, are positioned transversely of the groove. From this it happens that they often interfere with the operation of the McKay stitcher, by reason, for example, of the bar of a staple catching upon the hook or barb of the needle of the stitcher and breaking the needle or injuring 50 the thread.

It is an object of the present invention to provide an improved staple-inserting machine organized to insert staples in such a manner that the bars of the staples may be located in a predetermined position not neces-

sarily parallel with the position occupied by the bars when the staples are formed. In the illustrated machine this is done by means of a novel throat member or nozzle having a rifled passage extending therethrough, the 60 grooves of the rifling being arranged to engage the legs of the staples to control the position of the staples as they are moved through the nozzle into engagement with the work. Since the illustrated machine forms the 65 staples with their bars parallel to the front of the machine, and it is desirable, for example in McKay sole laying, to insert the staples with their bars at right angles to the front of the machine, the rifling of the throat 70 of the illustrated machine has a quarter twist, that is the rifling is in the form of a spiral turning through 90 degrees between one end of the nozzle and the other.

The novel shoe and method of McKay sole 75 laying disclosed herein are not claimed in this application since they are claimed in my co-pending application, Serial No. 139,437, filed October 4, 1926.

With the above and other objects and features in view, the invention will now be described with reference to the accompanying drawings and pointed out in the claims.

In the drawings,

Fig. 1 is a front elevation of the head of a 85 stapling machine embodying the invention, parts of the mechanism being shown in transverse section;

Fig. 2 is a plan view on an enlarged scale of the rifled nozzle of the machine of Fig. 1; 90

Fig. 3 is a vertical section on the line III—III of Fig. 2; and

Fig. 4 illustrates the manner in which a 95 staple is rotated as it is driven through the rifled nozzle of the machine.

The invention is illustrated herein as embodied in a machine for making and driving staples of the type disclosed in Letters Patent of the United States No. 1,016,930, granted Feb. 18, 1912, on an application of 100 William H. Borden. Since that patent discloses a well known commercial machine many of the parts of which form no part of the present invention, a complete description of the machine is not included in this specification. For such a complete description, reference may be had to said Letters Patent.

Among the parts of the illustrated machine (which parts are given herein the same reference characters as in said Letters Patent) 110

are a pair of feed rolls 90, 92 arranged to feed a wire *w* to a pair of suitably operated knives or cutters 80, 82, an inside former 30, an outside former 32, and a driver 18 carried by a driver bar 16. These parts may be and, as illustrated, are operated as set forth in said Letters Patent.

The illustrated machine is provided with a throat member or nozzle 40 having a driver-
10 passage 42, the entering end 44 of which is flared to facilitate the entrance of the staples. In accordance with the present invention, the driver passage of nozzle 40 is rifled as shown at 46 (Figs. 2 and 3), the rifling, which comprises a pair of oppositely disposed grooves, being in the form of a spiral having a quarter turn so as to rotate the staples through 90 degrees. The grooves of the rifling are arranged to engage the legs
15 of the staple as the staple passes through the nozzle, and to insure proper engagement of the staple legs with the rifling the flared entering end of the driver passage is provided a groove 48 converging toward the ends of
20 the grooves of the rifling. Thus if a staple should be somewhat displaced in its passage from the formers of the machine to the nozzle, nevertheless the ends of its legs will enter
25 groove 48 and will be guided to the grooves of the rifling 46.

In order to facilitate the turning of the staples about their longitudinal axes and relatively to the driver 18 as they are pushed by the driver through the nozzle, the leading
35 end of the driver is spherically concave, as illustrated at 50 (Fig. 3), the curvature of the cavity corresponding approximately with that of the bars of the staples which are to be inserted.

It will be seen that when, during the sole-laying operation as performed in the manufacture of a McKay shoe, the shoe is presented with its toe pointing toward the machine, the staples will be formed by the throat with their bars arranged transversely of the groove and channel, but in their passage through the nozzle into engagement with the sole of a shoe they will be turned through 90 degrees (as illustrated in Fig. 4) so that they are driven into the shoe *S* with their bars substantially parallel to the groove 52, preferably with the bars of the staples adjacent to the groove 52 but upon the shoulder 54 of the channel adjacent to the groove rather than in the groove itself. Fig. 4, moreover, illustrates at 56 a staple in the relation to the shoe at which it is formed with its bar arranged transversely of the groove, the ar-

rows indicating the manner in which the staple is rotated so that it is driven into the sole of the shoe with its bar parallel to the groove 52 as at 58. With the staple so located the possibility of the needle of the McKay stitcher catching upon the bars of the staple is much reduced and the consequent
65 breakage of needles and injury to the thread is to a large extent eliminated.

While the invention has been described herein with reference to a machine of the type disclosed in Letters Patent of the United States No. 1,016,930 and with reference to the use of that machine for McKay sole-laying, it should be understood that the invention is not limited to use in connection with machines of this type, nor to a machine for use
70 in McKay sole-laying, as evidently it can be embodied in other machines, for other purposes. Also it is not essential that the rotation of the staples, as they pass through the nozzle of the machine, be 90 degrees. Evidently by using other rifling, the extent of the rotation given to the staples may be varied as may be desired.

Having described the invention, what I claim as new and desire to secure by Letters Patent of the United States is:

1. A rifled nozzle for a staple-inserting machine with the grooves of the rifling arranged to engage the legs of staples bent from pieces of wire thereby to control the position of the staples as the staples are moved through the nozzle into engagement with the work.

2. A nozzle for a staple-inserting machine having a driver passage with a flared entering end, the driver passage being provided with rifling comprising a pair of oppositely disposed narrow spiral grooves arranged to receive the legs of a staple as the staple passes through the driver passage.

3. A fastening-inserting machine having an inside and an outside former arranged to form staples from pieces of wire fed thereto with the bar of each staple substantially parallel to the front of the machine, a driver arranged to drive the staples into a work piece, and a rifled throat member through which the staples pass after they have been formed and as they are driven arranged to rotate each staple about the line of drive through a pre-determined angle between the formation of the staple and its insertion into the work.

In testimony whereof I have signed my name to this specification.

GUY R. COYNE.
